UNITED STATES PATENT OFFICE.

WILLIAM A. BENSON, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

SERVICE OBSERVATION ARRANGEMENT FOR TELEPHONE SYSTEMS.

Application filed October 18, 1921. Serial No. 508,532.

To all whom it may concern:

Be it known that I, WILLIAM A. BENSON, a citizen of the United States of America, and a resident of Chicago, Cook County, and State of Illinois, have invented certain new and useful Improvements in Service Observation Arrangements for Telephone Systems, of which the following is a specification.

10 The present invention relates to service observation arrangements for telephone systems in general but is concerned more particularly with service observation arrangements for use in automatic telephone systems; and has for its object the provision 15 of new and improved circuit arrangements whereby the line of the complaining subscriber may be placed under the observation of an operator who without interfering 20 with his service in any way and without his knowledge is able to observe just how many calls he receives and also the number of successful and attempted calls he makes. In case his calls are unsuccessful, this operator 25 may also determine just why they are unsuccessful.

30 A special feature of the invention is the provision of a plurality of indicating devices, one for each digit of a called number, that indicate to the operator the number called by the subscriber whose line is under observation.

35 According to another feature of the invention, a recording device is provided which makes a record each time the subscriber whose line is under observation removes his receiver of how long the receiver is kept off the hook before a number is completely dialled. A record is made also 40 of the time that elapses between the dialing of the various digits of the called number.

45 The objects above set forth, together with others which will not be mentioned now, will be pointed out in detail in the course of the description of the accompanying drawings comprising Figs. 1 and 2, which when placed together with Fig. 1 above Fig. 2 and with the corresponding lines at the 50 adjacent sides thereof in alignment show by means of the usual circuit diagrams a sufficient amount of the apparatus employed in a system embodying the principles of the invention to enable the same to be under-

stood. Fig. 1, shows a subscriber's telephone together with a bell belonging to another telephone on the same line. This line terminates at the exchange in a protector as shown and normally extends from thence to an individual line switch C.

60 Fig. 2 represents certain equipment at the observing operator's position which is inserted between the line of a complaining subscriber and the individual line switch with which the said line is normally connected. The four conductors from Fig. 2 terminate in Fig. 1 in what is commonly known as a test shoe. This shoe is inserted in the desired protector in the manner shown and when so inserted includes the 65 equipment shown in Fig. 2 in series with the complaining subscriber's line.

70 The apparatus having thus been described in general will now be described in connection with a detailed description of its operation. For this purpose it will be assumed that someone calls the complaining subscriber on the line under observation which is the subscriber at the substation A. When the line in question is seized by a 75 connector at the bank contacts 25, 26, and 27, or their multiples, a ground potential is placed upon private normal conductor 6, thereby closing a circuit for switching relay 11 and stepping magnet 16 of the line switch C in series. Switching relay 11, upon energizing, disconnects the bridge which is normally across the conductors 4 and 5 at armatures 13 and 15, but owing to 80 a mechanical interlocking device between its armature and that of line relay 12 the armature of switching relay 11 is operated only about half way and consequently the 85 wipers of the line switch are not connected up. Stepping magnet 16 does not energize 90 in series with relay 11 on account of the relatively high resistance of the latter. Ringing current of the proper frequency is 95 now sent out over the bank contacts 25 and 27, conductors 4 and 5, conductors 4' and 5', the equipment at the observing operator's position, and conductors 2' and 3' to line conductors 2 and 3. This ringing current passes through the bells at substations A and A' but only the bell at the substation 100 A is operated, the other bell being tuned to a different frequency.

105 At the observing operator's position, part

2

of the ringing current passes through the bridged relays 31 and 33, but only relay 31, which is tuned to respond to this particular frequency of ringing current responds. Relay 31, upon energizing, closes a circuit for relay 32 at armature 48. Relay 32, upon energizing, locks itself up at armature 50 to conductor 87, which is grounded through the resting contact of armature 57 and said armature closes a circuit for relay 37 at armature 47; and closes a circuit for the lamp L at armature 49. The operator is apprised by the lighting of the lamp L of the fact that the subscriber at substation A is being signalled. Relay 37, upon energizing, prepares a locking circuit for itself at armature 97; closes a circuit for cut off relay 30 at armature 96; and at armature 95 places a shunt around armature 55 and its resting contact for a purpose to be explained more fully hereinafter. Cut off relay 30, upon energizing, removes the tuned relays 31 and 33 from in bridge of the line at armatures 44 and 46 so that they will not interfere with the ringing of the bell at the called substation. It will be noted that the ringing current passes through the relays 35 and 39 at this time. Relay 39 does not respond owing to its marginal adjustment and to the small number of turns in its lower winding. The armature of relay 35 is not appreciably affected by the current which passes through the said relay owing to the fact that the non-inductive resistance 58 is shunted around the relay at this time.

When the subscriber at substation A responds to the ringing of his bell by removing his receiver, a direct current bridge is closed across the conductors 2 and 3, whereupon the source of ringing current is removed by the connector switch and a source of talking current is connected up instead. The low wound series relay 35 at the observing operator's position which did not respond to the ringing current on account of the non inductive shunt around it now responds to the direct talking current by operating its armature 54, thereby closing a circuit for release relay 36. Relay 39 however, being marginally adjusted does not respond at this time owing to the fact that its armature cannot be attracted until current flows through both the upper and lower windings in the same direction. Release relay 36, upon energizing, opens a point in the shunt around relay 35 at armature 55 but the said shunt is still closed through armature 95 and its working contact; prepares a circuit for relay 38 at armature 56; and at armature 57 opens the locking circuit of relay 32 and places ground upon conductor 86. Relay 32, upon deenergizing, opens another point in its circuit at armature 50; opens the circuit of the lamp L at armature 49; and at armature 47 opens the initial energizing circuit of relay

37 and closes the following locking circuit for the said relay 37: from ground by way of conductor 86, working contact of armature 97 of relay 37 and said armature, normally closed contacts controlled by armature 47, normally closed contacts controlled by armature 73, and relay 37 to battery. When ground is placed upon conductor 86 a circuit is closed for the upper winding of electro polarized relay 39. Relay 39, however, is not energized at this time owing to the fact that the current flowing in either winding opposes that flowing in the other. A branch of this circuit extends also by way of armature 62 and its resting contact to the lamp L' which becomes lighted to notify the observing operator that the called subscriber has answered. Another branch of this circuit extends from conductor 86 by way of armature 59 of relay 38 and its resting contact and armature 69 and its resting contact to battery, by way of magnet 90 of the recorder R. Magnet 90, upon energizing, attracts its armature 91, thereby forcing the pencil 93 into engagement with the moving tape 92. This tape it may be said is suitably marked and dated so that a record as to what time and upon what day a call was made or received can be had. A mark is made on the tape the length of which depends upon the length of time during which the magnet 90 is energized.

The called subscriber, of course, may begin to converse with the calling subscriber as soon as he removes his receiver and is not aware of any of the events which are taking place at the recording operator's position. As much as is shown of the talking circuit is outlined by heavy conductors and it will be observed that it includes the lower winding of relay 39. The lower winding of relay 39, however, has comparatively little impedance and consequently does not appreciably interfere with the transmission of voice currents.

When the conversation is completed the calling and called subscribers replace their receivers. When the receiver is replaced at the substation A the circuit of relay 35 is opened and the said relay, upon deenergizing, opens the circuit of relay 36 whereupon relay 38 energizes in series with relay 36 and opens the circuit of the magnet 90 of the register R at armature 59. Magnet 90, upon deenergizing, removes the pencil 93 from engagement with the tape 92 thus terminating the mark being made on the latter. As a further result of the energization of relay 38 it places the operating magnet 75 of the switch D in multiple with release relay 36 at armature 58, the circuit including armature 64 and its resting contact. Owing to the high resistance of relay 38, operating magnet 75 does not energize and release relay 36 deenergizes. Upon deenergizing, re-

lease relay 36 opens the circuit of relay 38 at armature 56 and removes ground from conductor 86 at armature 57. Relays 37 and 38 now deenergize and the lamp L^2 5 comes extinguished.

The operator upon noting that the lamp L^2 has become extinguished knows that the conversation has terminated and that the called subscriber has replaced his receiver. 10 She may make out a ticket if desired or in any suitable way record the information that she has gathered.

In regard to the line switch C it may be said that switching relay 11 deenergizes upon 15 the release of the connector switch which was used to complete the connection, and upon so doing restores the conditions in the line switch C to normal.

It will be assumed now that the subscriber 20 at substation A desires to call some other subscriber. When the receiver is removed at substation A, a circuit is closed over the line conductors 2 and 3, conductors 2' and 3', the equipment at the observing operator's 25 position, conductors 4' and 5', and conductors 4 and 5, for line relay 12 of the line switch C. Line relay 12, upon energizing, places ground upon private normal conductor 6 at armature 18, thereby closing a 30 circuit for switching relay 11 and stepping magnet 16 in series and at armature 17 connects the test wiper 21 to a point between the said switching relay 11 and the said stepping magnet 16. The line switch C now 35 operates in the well known manner to select an idle trunk line leading to a first selector and when one is found the switching relay 11 energizes, not having energized before 40 on account of being short circuited by the ground potential which is encountered by test wiper 21 in passing over busy test contacts. Switching relay 11, upon energizing, disconnects the line conductors 4 and 5 from the winding of line relay 12 and ground 45 respectively and extends them by way of armatures 13 and 15 and wipers 20 and 22 to the line relay of the first selector to which the trunk line upon which the wipers are extending at this time. The line and release 50 relays of the said selector now energize in the well known manner and the latter places ground upon the associated release trunk conductor, thereby closing a holding circuit 55 for the switching relay 11 in the usual manner.

In the equipment at the recording operator's position, relay 39 does not energize for reasons hereinbefore given but relay 35, upon energizing, closes a circuit for relay 36 at armature 54. Relay 36, upon energizing, removes the resistance 58 from in shunt of relay 35 at armature 55; prepares a circuit 60 for relay 38 at armature 56; disconnects ground from conductor 87 and places ground upon conductor 86 at armature 57. In re-

sponse to the placing of ground upon conductor 86 the lamp L^2 becomes lighted to apprise the operator of the fact that a subscriber has his receiver off the hook. A circuit is closed through the upper winding of 70

electro polarized relay 39 at this time but the said relay does not energize for hereinbefore given reasons. As pointed out before the placing of ground upon conductor 86 closes a circuit through armature 59 and its 75 resting contact and armature 69 and its resting contact for the magnet 90 of the register R, with the result that armature 91 is attracted and the pencil 93 begins to make a mark upon the moving tape 92. As a 80 further result of placing ground upon conductor 86 a circuit is closed for cut off relay 30 including the resting contact of armature 96 and said armature. Cut off relay 30, upon energizing, disconnects the 85 tuned relays 31 and 33 at armatures 44 and 46.

The calling subscriber may now operate his calling device in accordance with the first digit of the desired number, thereby 90 producing a corresponding number of interruptions in the circuit of the line relay of the first selector to which the connection has been extended. In response to these interruptions the said line relay causes the selector to raise its wipers to the desired level and rotate them in search of an idle trunk line leading to a connector switch, assuming of course, that this is a 1000 line system. In 95 the equipment at the observing operator's position, relay 35 falls back each time an interruption is produced in its circuit and, upon falling back in response to the first interruption, removes a short circuit from around relay 38. Relay 38, upon energizing, in series with release relay 36, removes ground from the upper set of wipers of the switches D—D², inclusive, at armature 60; opens the circuit of the magnet 90 of the register R at armature 59; and at armature 58 places the operating magnet 75 of the switch D in multiple with release relay 36. Operating magnet 75, however, does not energize at this time on account of the high 100 resistance of relay 38. Relay 35, upon energizing, following the interruption produced in its circuit, short circuits relay 38 and closes a circuit for relay 36 and operating magnet 75 in multiple at armature 54. Magnet 75, upon energizing, advances the 105 wipers of the switch D into engagement with the first set of bank contacts. Relay 38, being short circuited, does not fall back immediately and consequently retains its armatures attracted throughout the series of interruptions. When relay 35 deenergizes in response to the second interruptions produced in its circuit magnet 75 deenergizes not being able to retain its armature attracted in series with the high resistance 110 re-

115

120

125

130

4
lay 38. Operating magnet 75 is energized again each time relay 35 energizes and by its subsequent operation advances the wipers of the switch D into engagement with the set of bank contacts corresponding to the digit called. At the end of the series of interruptions relay 35 comes to rest in an energized condition, whereupon relay 38 deenergizes and opens the circuit of operating magnet 75 at armature 58; closes the circuit of the magnet 90 of the register R at armature 59 thus starting another mark on the tape 92; and at armature 60 places ground upon the upper set of wipers of the switch D-D², inclusive, thereby closing the following circuit for relay 40: From ground by way of armature 57 and its working contact, armature 60 and its resting contact, upper wiper of the switch D, the bank contact upon which the said wiper is resting, normally closed contacts controlled by armature 63, and relay 40 to battery. Relay 40, upon energizing, closes a locking circuit for itself and disconnects itself from the wiper of switch D at armature 63, and at armature 64 shifts the operating circuit from magnet 75 of the switch D to the magnet 76 of the switch D'.

In response to the calling of the second digit in the desired number the connector switch to which the connection has been extended raises its wipers step by step until they stand opposite the level of contacts in which the desired line terminates.

In the equipment at the observing operator's position the pencil 93 of the register R is raised from the tape 92 during the calling of this digit in the same manner as before and the operating magnet 76 of the switch D' operates in the same manner as the magnet 75 of the switch D operated during the calling of the previous digit and steps the associated wipers around to the set of bank contacts corresponding to the digit called. At the end of this digit relay 38 falls back as before with the result that the pencil 93 of the register R is brought into engagement with the associated tape again; the circuit of operating magnet 76 is opened; and ground is placed upon the upper set of wipers of the switches D, D' and D². This ground potential extends by way of the upper wiper of the switch D', the bank contact with which it is in engagement, normally closed contacts controlled by armature 65, and relay 41 to battery. Relay 41, upon energizing, locks itself to conductor 86 and disconnects itself from the wiper of the switch D' at armature 65, and at armature 66 transfers the operating circuit to the operating magnet 77 of the switch D².

In response to the calling of the next and last digit in the desired number the connector switch to which the connection has been extended rotates its wipers step by step until they come to rest upon the bank contacts in

which the desired line terminates. The connector switch now sends out ringing current intermittently to ring the bridged bell at the called substation.

At the observing operator's position the results produced by the calling of the final digit are similar to the results produced by calling the previous digit and consequently the operating magnet 77 responds by rotating the wipers of the switch D² into engagement with the set of bank contacts corresponding to the digit called. At the end of this series of interruptions relay 38, upon falling back, in addition to the other operations performed, places ground upon the wipers of the switches D-D², inclusive, thereby closing a circuit for relay 42 including the upper wiper of the switch D² and the normally closed contacts controlled by armature 68. Relay 42, upon energizing, locks itself to conductor 86 and disconnects itself from the wiper of the switch D² at armature 68; shifts the operating circuit from magnet 77 of the switch D² to battery through the resistance 93 at armature 70; opens the circuit of magnet 90 of the register R at armature 69; and at armature 67 disconnects the lamp L² from the working contact of armature 62 and connects up the lamp L⁴ instead.

When the called subscriber answers, the connector switch in a well known manner reverses the current flow in the incoming trunk conductors and consequently in the conductors leading back through the equipment at the observing operator's position to the calling substation. When this occurs the two windings of electropolarized relay 39 which heretofore have opposed each other now assist each other in operating the said relay. Relay 39, upon energizing, replaces the resistance 58 in multiple with relay 35 at armature 61. This is done so as to afford a better path for the voice currents. As a further result of the energization of relay 39 it disconnects the lamp L² and connects up the lamp L⁴ at armature 62 whereupon the lamp L² becomes extinguished and the lamp L⁴ becomes lighted to inform the operator that the called subscriber has answered. The calling and called subscribers may now converse with each other as desired, as much of the talking circuits as are shown being outlined by the heavy conductors.

The observing operator not only knows that the calling subscriber has called a number and that his call has been answered but also knows what number he has called. This is made possible by the bank of lamps which is suitably arranged before her so as to display the called number. This bank of lamps is connected one to each contact over which the lower wipers of the switches D-D², inclusive, pass, and consequently one lamp

from each switch is lighted, as soon as the switch is operated, to show the position of the wipers of that switch, which in turn is indicative of the number called. Of these 5 lamps, only one for each switch is shown, the others, which are connected in the same manner as the one shown, being omitted for the sake of simplicity.

When the conversation is finished the calling 10 and called subscribers replace their receivers. When the receiver is replaced at the substation A, the circuit of the line relay of the connector through which the connection has been extended is opened where- 15 upon the automatic switches are restored to normal in the usual manner. At the observing operator's position relay 35 deenergizes in response to the replacing of the receiver at the calling substation and opens the circuit 20 of release relay 36 whereupon relay 38 energizes in series with the said relay 36 and places resistance 93 in multiple with release relay 36 at armature 58. Resistance 93 is lower than the resistance of relay 36 and 25 most of the current which comes through the high wound relay 38 flows through the said resistance 93. As a result release relay 36 deenergizes and upon so doing opens the circuit 30 of relay 38 at armature 56, whereupon relay 38 deenergizes also. As a further result of the deenergization of release relay 36 it removes ground from conductor 86 whereupon relays 40-42, inclusive, deenergize and the lamp L⁴ becomes extinguished. 35 As a further result of the removal of ground from conductor 86, cut off relay 30 deenergizes and connects up the tuned relays 31 and 33 at armatures 44 and 46. As a still further result of the deenergization of release relay 36, it places ground upon conductor 87 at armature 57, thereby closing a 40 circuit for release magnets 78, 79, and 80 in multiple through the off-normal contacts 81, 82, and 83. By the operation of these release magnets the wipers of the switches D, D', and D² are restored to normal position, the circuit of each of the release magnets being broken at its associated off-normal contacts when the associated wipers reach 45 normal position. The entire apparatus is now restored to normal position and is ready for another call either incoming or outgoing.

From an examination of the drawings it may be seen that when a subscriber at 50 substation A' is called the operation of the equipment at the observing operator's position is the same as when the subscriber at substation A is called with the exception that the tuned relay 33 responds in this case and closes a circuit for the associated relay 34. Relay 34, upon energizing, closes a locking circuit for itself, closes a circuit for relay 37, and closes a circuit for the lamp L'. Since the subscriber at sub-

station A' has made no complaint regarding 65 his service the operator need not pay any attention to the lighting of the lamp L'.

It sometimes happens that the conductors of a trunk line become accidentally reversed. This may not cause any trouble 70 to arise in some cases but when the connection is extended through an automatic repeater the reversal of current which occurs when a trunk line is selected in which the conductors are reversed causes the operation 75 of certain relays in the repeater which render the impulse repeating circuit inoperative and consequently prevents the connection from being extended any further. If the subscriber whose line is under ob- 80 servation, is making a call and one of the selecting switches in the exchange cuts through upon a reversed trunk the electro- polarized relay 39 at the recording operator's position immediately energizes and 85 extinguishes the lamp L². Since all of the digits of the desired number have not yet been called relay 42 will not be energized and the lamp L³ is lighted instead of the lamp L⁴ which lights upon the response of 90 the called subscriber. The operator, upon noting the lighted condition of the lamp L³, throws the key K, which is a combined release and holding key, into holding position, thereby bridging the impedance coil 95 45 across the conductors 2' and 3' so as to hold up the connection in case the calling subscriber replaces his receiver. The operator now observes the indicating lamps and determines what route the call has taken 100 and how many digits have been called. This information she gives to an attendant who makes haste to find the reversed trunk. As soon as the attendant has discovered 105 which trunk is in trouble he may release the switch through which the connection is extended to it and make the trunk busy until he has time to clear up the trouble. As soon as the attendant has located the 110 trunk which is giving the trouble he notifies the observing operator who, after throwing the key K', which is a combined listening and monitoring key, to listening position, explains the cause of the delay to the calling subscriber and releases the partly established connection by throwing the key K to the opposite position. When the connection is released the operator restores the key K to normal and tells the calling subscriber that he may proceed again to call the 115 desired number in the usual manner.

In case the observing operator suspects 120 that the speed of the subscriber's calling device is too high or too low, she may test the speed by operating the key K² which 125 connects a calling device speed indicator to the operating lead. Such a speed indicator is disclosed in detail in the U. S. Patent

of John Erickson, No. 1,112,994, granted Oct. 6, 1914. After the key K^3 is operated, the impulses which are delivered to the associated operating magnets, are delivered also to the escape magnet of the speed indicator which automatically indicates to the observing operator the speed of the calling subscriber's calling device relative to a fixed standard.

10 It may occur that the fault which prevents a subscriber from setting up a desired connection lies in the line switch in which his line terminates. If the observing operator suspects that such is the case, she 15 may operate the key K^2 , thereby disconnecting the line switch C and connecting up another line switch to which the leads 71 and 72 associated with the key K^2 are assumed to extend. This other line switch, 20 of course, may be identical with the line switch C, Fig. 1. If the operator observes that the calling subscriber always gets his number when this other line switch is connected up but not when the line switch C 25 is connected up, she may reasonably assume that the trouble lies in the line switch C, and may make a report to an attendant who will determine if her assumption is correct.

30 The various features of the invention having been described will now be pointed out in the appended claims.

What I claim is:

1. In an automatic telephone system, a 35 plurality of subscriber's lines, means including automatic numerical switches for setting up a connection from a calling one of said lines to a called one of said lines, means for placing a certain line under observation, and means operated only during 40 the setting up of a connection from the line under observation for displaying the number of the called line.

2. In a telephone system, a calling subscriber's line terminating at one end in a subscriber's instrument and at the other end in an automatic switch, a plurality of other lines, means including said switch for setting up a connection between the calling line and 50 one of said other lines, a relay inserted in said calling line between the subscriber's instrument and said automatic switch, and means controlled by said relay for displaying the number of the line with which the 55 calling line is connected.

3. In a telephone system, a plurality of subscriber's lines, means including subscriber controlled numerical automatic switches for setting up a connection from a 60 calling to a called one of said lines responsive to the calling of the digits in the number of the called line, means for placing a certain line under observation, a digit space time recorder, and means for operating said time recorder whenever a connection is be-

ing set up from the line under observation to another line.

4. In a telephone system, a plurality of subscriber's lines, means including subscriber controlled numerical automatic 70 switches for setting up a connection from a calling to a called one of said lines responsive to the calling of the digits in the number of the called line, means for placing a certain line under observation, a time recorder, means for operating said time recorder rendered effective whenever a call is initiated from the line under observation, and means for rendering said last named means inoperative during the calling of each 75 digit in the number of the called line.

5. In a telephone system, a plurality of subscriber's lines, means including subscriber controlled numerical automatic switches for setting up a connection from a calling to a called one of said lines responsive to the calling of the digits in the number of the called line, means for placing a certain line under observation, a digit space time recorder, means for operating 80 said time recorder whenever a connection is being set up from the line under observation to another line, and means for rendering said last named means inoperative after the calling of the last digit in the number of 85 the called line.

6. In a telephone system, a subscriber's line terminating at the exchange in an automatic switch, means including said switch and other switches controlled by the subscriber on said line for extending a connection to another line, and means for automatically notifying an operator at the exchange 90 of the number of the called line.

7. In a telephone system, a subscriber's line terminating at the exchange in an automatic switch, means including said switch and other switches controlled by the subscriber on said line for extending a connection to another line, an operator's position, 100 and means for automatically advising the operator at said position as to which line in the exchange the said subscriber is connected with.

8. In a telephone system a subscriber's line terminating at the exchange in an automatic switch, means including said switch and other switches controlled by the subscriber on said line for extending a connection to another line, an operator's position, and means for displaying the called number to the operator as soon as the connection is 110 completed.

9. In a telephone system, a subscriber's line terminating at the exchange in an automatic switch, means including said switch and other switches controlled by the subscriber on said line for extending a connection to another line, an operator's position, and means for registering the digits in the 115 120 125 130

number of the called line as fast as they are called to notify the operator what line the said subscriber is connected with.

10. In a telephone system, a subscriber's line terminating at the exchange in an automatic switch, means including said switch and other switches controlled by the subscriber on said line for extending a connection to another line, a relay responsive to 5 all the digits of the called number, and a plurality of digit registering devices controlled by said relay.

11. In a telephone system, a subscriber's line terminating at the exchange in an automatic switch, means including said switch and other switches controlled by the subscriber on said line for extending a connection to another line, a relay responsive to all 15 the digits of the called number, a plurality 20 of digit registering devices controlled by said relay and a plurality of groups of digit display lamps controlled by said registering devices.

12. In a telephone system, a subscriber's line terminating at the exchange in an automatic switch, means including said switch and other switches controlled by the subscriber on said line for extending a connection to another line, a relay responsive to all 25 the digits of the called number, means controlled by said relay for registering the different digits, and means for transmitting the complete number to an operator.

13. In a telephone system, a subscriber's line terminating at the exchange in an automatic switch, means including said switch and other switches controlled by the subscriber on said line for extending a connection to another line, a relay responsive to 30 40 all the digits of the called number, an operator's position, and means controlled by said relay for registering the complete number and for displaying the same at said position.

45. 14. In a telephone system, a calling subscriber's line, automatic switches controlled by the calling subscriber in accordance with the digits in a called number to extend a connection to another line, and means at the 50 exchange for making a record of the time intervals which elapse between the calling of successive digits.

55. 15. In a telephone system, a calling subscriber's line, automatic switches controlled by the calling subscriber in accordance with the digits in a called number to extend a connection to another line, a recording device at the exchange for registering the length of the time intervals which elapse between the calling 60 of successive digits, and means for automatically starting said device when the call is initiated.

65. 16. In a telephone system, a calling subscriber's line, automatic switches controlled by the calling subscriber in accordance with

the digits in a called number to extend a connection to another line, a recorder at the exchange comprising a moving tape and means for marking the same, means for bringing said marking means in contact with the tape 70 when the call is initiated, and means for separating said marking means from the tape during the calling of each digit of the number.

17. In a telephone system, a subscriber's line terminating at the exchange in an automatic switch, means including said switch and other switches controlled by the subscriber on said line for extending a connection to another line, an impulse sender at the station on said line by means of which said switches are controlled, an operator's position, means for notifying the operator when the call is initiated, an impulse speed indicator, and means whereby the operator 80 85 can cause said indicator to be operated simultaneously with said switches.

18. In a telephone system, a subscriber's line terminating at the exchange in an automatic switch, means including said switch and other switches controlled by the subscriber on said line for extending a connection to another line, an impulse sender at the station on said line by means of which said switches are controlled, an operator's position, means for notifying the operator when the call is initiated, and a speed indicator at the operator's position for indicating to the operator the rate at which impulses are 90 95 transmitted to said switches.

19. In a telephone system, a subscriber's line terminating in an automatic switch for use when said line is calling, other switches for connecting with the said line when the same is called, a relay connected in series with the said line between the subscriber's station and said first switch and operated over the two sides of the said line in series registering mechanism controlled by said relay, and circuit arrangements for shunting said relay responsive to the said line being connected in a conversational circuit either as a calling or a called line, said relay not being shunted when said line is a calling line and the desired connection is in process 105 110 115 of being established.

20. In a telephone system, a line extending from a manual switchboard to an automatic switch, means including said switch and other switches for extending connection to a called line, means for reversing the direction of current flow in the said line when the called subscriber answers, an answering supervisory signal responsive to the reversal, another supervisory signal, 120 125 and means for operating the other signal in case the direction of current flow in said line is reversed before the called line is connected with.

21. In an automatic telephone system, a 130

party line, an operator's position and means for notifying the operator when the line is calling or being called, said means serving also, in case the line is being called, for 5 notifying the operator which of the several parties on the line is wanted.

22. In an automatic telephone system, a subscriber's line, subscriber controlled automatic switches for extending a connection 10 to another line, an operator's position, and means at said position individual to said subscriber's line for notifying the operator when the call is initiated, when the first directly controlled switch involved in 15 the connection is operated, when the connection is completed, and when the called subscriber answers.

23. In an automatic telephone system, a subscriber's line, subscriber controlled automatic switches for extending a connection 20 to another line, an operator's position, and visual means for notifying the operator when the call is initiated, when each directly controlled switch involved in the connection is operated, and when the called subscriber answers.

24. In a telephone system, a subscriber's line extending by way of a manual switchboard to an automatic switch, means including 30 said switch and other switches controlled by the subscriber on said line for extending connections to called lines, means for notifying the operator when said first switch is out of order, another switch, and 35 means at said switchboard whereby the operator can substitute said last switch for said first switch to enable the subscriber to call.

25. In a telephone system, a plurality of 40 subscriber's lines, means including subscriber controlled numerical automatic switches for setting up a connection from a calling to a called one of said lines responsive to the calling of the digits in the number of the called line, a time recorder, 45 means for placing a certain line under observation and for connecting said recorder

therewith, and means for operating said time recorder after the subscriber on the line under observation has responded to a 50 call.

26. In a telephone system, a protector on the distributing frame at the exchange, a subscriber's line normally connected through 55 said protector and terminating in an automatic switch, a link circuit, and means for inserting said circuit at said protector to include same in series with said line for observation or testing purposes.

27. In a telephone system, a protector on 60 the distributing frame at the exchange, a subscriber's line normally connected through said protector and terminating in an automatic switch, observation equipment including means for signaling an operator on 65 calls incoming to and outgoing from said line, and means for inserting said equipment at said protector to include same in series with said line for observation purposes.

28. In a telephone system, a protector on 70 the distributing frame at the exchange, a subscriber's line normally connected through said protector and terminating in an automatic switch, a test shoe, a link circuit having both ends terminating in said shoe, said 75 shoe adapted to be inserted into said protector to include said circuit in series with said line, and means in said link circuit for enabling an operator to supervise incoming and outgoing calls to and from said line. 80

29. In a telephone system, a protector on 85 the distributing frame at the exchange, a subscriber's line normally connected through said protector and terminating in an automatic switch, a test shoe, observation equipment connected to said shoe via a four conductor cord, said shoe adapted to be inserted into said protector for including said equipment between the subscriber and said switch for observation purposes. 90

In witness whereof, I hereunto subscribe my name this 10th day of October, A. D., 1921.

WILLIAM A. BENSON.
